UNITED STATES PATENT OFFICE.

KENNARD KNOTT, OF CHICAGO, ILLINOIS.

STEAM-VALVE.

SPECIFICATION forming part of Letters Patent No. 369,797, dated September 13, 1887.

Application filed September 20, 1886. Serial No. 213,977. (No model.)

To all whom it may concern:

Be it known that I, KENNARD KNOTT, of Chicago, in the county of Cook and State of Illinois, have invented certain new and useful Improvements in Slide-Valves, of which the following is a description, reference being had to the accompanying drawings, in which—

Figure 1 is a plan view of a cylinder and steam-chest to which my improved valve is applied. Fig. 2 is a vertical sectional view of the steam-chest, taken upon the line $x x$, Fig. 1, viewed in the direction of the arrow there shown, the slide-valve and dead-plate being removed. Fig. 3 is an end view with the cylinder-head removed and the remainder partly broken away and partly in section. Fig. 4 is a side view of the steam-chest with its dead-plate and valve removed and portions of the remainder broken away to show the location of the steamways. Fig. 5 is a central sectional view of the cylinder and steam-chest, taken upon the line $y y$, Fig. 3. Fig. 6 is a like sectional view in detail of the valve and steam-chest, showing the "dead-plate" in a reversed position from that in Fig. 5. Fig. 7 is a like view to that shown in Fig. 6 of a modification of said invention, showing one means of obtaining a larger exhaust. Fig. 8 is a sectional view upon the line $z z$, Fig. 7, representing a face view of the valve with a portion broken away to show the dead-plate. Fig. 9 is a rear view of the valve, and Fig. 10 shows a modified form of valve and dead-plate.

Like letters of reference indicate like parts in the different figures.

The object of my invention is to dispense with what is commonly known as the "link-motion" in steam-engines, and to provide a simpler, less expensive, and equally effective means for reversing the movement of the engine when desired.

To this end my invention consists in providing a double slide-valve with a double set of steam ways and ports and a removable and reversible plate so arranged that by the movement of a suitable lever one set of admission-ports may be opened and the other set closed, and vice versa, thereby permitting the steam to be introduced upon the other side of the cylinder at will, all of which is hereinafter

more particularly described, and definitely pointed out in the claims.

A in the drawings represents a steam-cylinder having a piston, A', Fig. 5, and piston-rod a .

B is a steam-chest having steam supply ports C C' D D' and exhaust-ports E E'. The supply-port C connects with a steam passage or way, C², Fig. 4, leading to the opposite end of the steam-chest, where it emerges into an enlarged passage, C³, with which the port C' also connects. Said way C³ is connected with the cylinder behind the piston, preferably by passing around the end through a suitable offset or projection, A², as shown in Fig. 4 and indicated in dotted lines in Figs. 2 and 5.

The ports D D' unite in a common central passage, D², Figs. 4, 5, and 6, which leads to the front of the steam-chest, and, like the way C², passes around the end through an offset, A³, into the front end of the cylinder A.

The exhaust-ports E E' unite at one end in a common way, E², Figs. 3, 4, and 5, which, after passing partially around the cylinder, is connected with the exhaust-pipe E³, Figs. 1 and 2.

From the foregoing it is obvious that if the ports C D' be normally closed and the steam alternately admitted into the ports C D, and assuming that there be a proper exhaust, the piston must thereby be reciprocated. This would manifestly be the result if the ports C D were closed and the ports C' D' alternately opened.

To enable me to accomplish this result, I provide a loose or sliding plate, F, Figs. 5 and 6, designated by me as a "dead-plate," which I insert between the ports described and the slide-valve, and which forms the valve-seat. Said dead-plate is provided with a series of admission-ports, 1, 2, 3, 4, 5, and 6, Figs. 5 and 6, said ports being so arranged in the plate with reference to said ports C D E and C' D' E' that when the ports 1 2 3 are opposite the ports C E D the ports D' E' C are closed, and vice versa. Attached to one end of said plate F is a rod, f, which is connected with a hand-lever, F', pivotally attached to a bracket, F², the upper part of which is formed in a sector shape and provided with notches

f' for the reception of an ordinary spring-catch, *f*². By means of said lever the dead-plate may be moved in either of the positions described, so that one set of ports may be closed and the other set opened at will, the plate being retained in either position by means of said catch. In connection with said dead-plate and double ports I employ a double slide-valve, which is constructed and arranged as follows: *G* is the usual rod protruding through the steam-chest, to which is rigidly attached, by means of a set-screw, a collar, *g*, Figs. 5 and 6, as well as a double steam-valve, the respective ends of which constitute distinct valves, (marked *G'G²*), constructed in the usual way, (except the steamway-connection between the two, hereinafter described,) the whole being preferably formed in one piece provided with a separation or slot between them for the admission of steam, the width of which slot corresponds to that of one of the steam-ports *D D'*.

Instead of making the offsets *A² A³* upon the respective ends of the cylinder, the steamways *D² C³* may be carried into the cylinder, as shown in Fig. 7, thereby leaving the cylinder-heads in the usual form.

As it is important to provide ample means for exhausting the steam in order to prevent undue compression, I have shown two ways of accomplishing that end--the first by making the ports *E E'* longer than the others, as shown in Figs. 2 and 4, and, secondly, by enlarging the spaces 2 and 5, respectively, as shown in Fig. 7, so that a portion only of the plate of the width of the lap of the valve is left in each place, and forming steamways *G³ G³* in the valve itself, so that upon the movement of the valve the distance of the width of its lap the steam will exhaust simultaneously into the ports *E E'*, regardless of which set of receiving-ports be open.

I do not confine myself to an oblong dead-plate arranged to be reciprocated, as it is obvious that the same may be made round, if

desired, with a valve corresponding in shape, as shown in Fig. 10, in which case the valve may be caused to oscillate by connecting therewith a crank, *g'*, and attaching the valve-rod *G* thereto, though I prefer the construction 50 heretofore described.

The operation of said valve is as follows: When a forward movement of the engine is desired, the dead-plate should be placed in the position shown in Fig. 5, in which event the 55 piston is operated through the medium of the ports *C' D' E'*. Upon moving said plate as described, the remaining set of ports are opened and the engine is caused to run backward. In the former case the part *G²* and in 60 the latter the part *G'* of the valve becomes operative.

Having thus described my invention, I claim—

1. The combination, with a cylinder having 65 double ports and steamways, of a movable dead-plate arranged to alternately open one set and close the other set of ports, and a double slide-valve having steamways therein connecting the two exhaust-chambers, where- 70 by the compressed steam from the cylinder may simultaneously escape from both exhaust-ports.

2. In combination with a cylinder having two sets of steam ports and ways, a double valve having one or more steam ways or channels connecting the exhaust-chambers and arranged to operate alternately with either set of ports as the same may be open, respectively, and a dead-plate having openings therein corresponding in number to said ports, the openings connecting with the exhaust-ports being so enlarged that the exhaust-steam may escape through both at the same time, substantially as and for the purposes specified. 80

KENNARD KNOTT.
